SHEET FEEDING DEVICE

Georg Spiess, Leipzig, Germany

Application May 3, 1938, Serial No. 205,788
In Germany May 4, 1937

4 Claims. (Cl. 271—53)

This invention relates to a sheet feeding device.

There are devices of this class known, in which the feed of a sheet from the pile, through an endless conveyor belt and a stationary checking means pressed against the belt at increasing pressure in feeding direction and stressing the elasticity thereof, and an adjustable pressure means can be regulated in such manner that the 5 sheets are selectively advanced either one behind the other in spaced relation or with any degree of overlapping.

Other devices for overlapped sheet feeding employ a regulating gear for varying speed and 10 thereby the degree of overlapping, or they are equipped with two gearings, selectively and alternately engageable by clutches, for the drive of the conveying means of the feed table, one of said gearings having a high ratio for retarding 15 the speed of the sheets and the other one a low ratio and invariable speed.

Compared with the known art, the invention has for its object to provide an arrangement for regulating the speed of the conveying means of 20 the feed table in conjunction with periodic retardation of the sheet travel towards the end of the feeding operation so as to permit the transition from overlapped stream to single feeding, and vice versa, without any coupling of the sheet 25 feeding means and, further, a reduction of the masses to be accelerated and retarded. For this purpose, both high speed feeding means for single feeding and low speed feeding means for overlapped feeding together with the associated adjustable pressure means are provided on the feed 30 table in such manner, for instance alternately succeeding each other in the direction of travel of the sheets, that they possess a single joint drive and a control device by means of which the pressure means, as rolls or balls, are selectively 35 pressed against the low or high speed feeding means to effect a corresponding rate of feeding. It is therefore not necessary any more to disengage and engage drives, which involves the stopping and starting of not inconsiderable masses, 40 as uniform driving of the sheet feeding means is insured and the manner of feeding may be altered without interrupting the feeding drive.

Another feature of the invention is that the low 45 speed and not the high speed conveying means are retarded in known manner for forwarding the sheets to the front gauges and are subsequently accelerated again, the sheets fed at higher speed being retarded by automatically turning each sheet toward the end of the feeding opera-

tion over to the slower moving and retarded conveying means. In order absolutely to insure soft sheet contact each sheet may be temporarily arrested by a stop placed in the path of the sheet when the pressure means are lifted off from the high speed feeding means and withdrawn again while the pressure means are set upon the slow speed feeding means. For overlapped feeding the pressure means are fixed in the position at which they contact with the slow speed feeding 10 means and are secured against being acted upon by the control means.

This reversal by hand of the pressure means regulating the sheet feed to the front gauges is connected with the reversal of the timing roller 15 determining the beginning of the feeding operation. The control of the timing roller or rollers is arranged for single feeding and, for overlapped feeding, must be adjusted at a position of the rollers at which they contact with the feeding 20 means.

As far as between the timing rollers and the pressure means for the feeding of the sheets to the front gauges additional pressure means for securing sheet feeding are required, they are provided for the low speed as well as high speed feeding means and so arranged that they can be selectively brought into operating or non-operating position. This reversal is preferably connected with the reversal of the previously mentioned pressure means.

The feed table according to the invention is preferably of the roller type with alternate arrangement of the slow and high speed conveying means in the direction of travel of the sheet, 35 whereby the reversible arrangement of the pressure means is facilitated.

By way of example, one form of the invention is illustrated in the accompanying drawings, in which all parts not required for understanding 40 the invention are omitted and in which Figures 1 and 2 are, respectively, an elevation and a plan of the general arrangement of the feeder with all unnecessary and complicating details omitted; and

Figs. 3 and 4 are views on an enlarged scale showing the drive of every first feed roller at low and high speed and the arrangements for reversing the pressure means for single feeding and for their automatic reversal at this manner of feeding; more particularly, Fig. 3 showing the adjustment of the feeder for single feeding and Fig. 4, for overlapping feed.

The sheets are forwarded from the pile 1 by a separating and feeding device 2 indicated in Fig. 55

1 and engaging for instance the rear edge of the sheets to the conveying means of the transmitting table of the roller type whose rollers, beginning at the pile, are alternately designated 4 and 5 in the direction to a machine, for instance the cylinder 3 of a printing machine. The rollers 4 comprising also the first roller with which the rollers 6 coact in known manner to start feeding are driven at a speed corresponding to overlapping feed. Joint driving of the rollers 4 is effected by causing the rollers 4 each provided with a toothed wheel 7 on one side to mesh in pairs with an intermediate gear 8. The pinion of the first roller 4 is driven by a single revolution control shaft 9 through the medium of a gear periodically effecting retardation and acceleration. This gear comprises a toothed wheel 10 eccentrically secured relative to the driving shaft 9 and transmitting its drive through a planet wheel 11 to a toothed wheel 11a of the first roller 4. The planet wheel 11 is arranged on the link pin of a joint formed by the arms 12, 13, the arm 12 swinging about the pin of the eccentric wheel 10 and the arm 13 about the axis of the toothed wheel 7 of the first feed roller 4. Owing to this drive, all rollers 4 are periodically retarded and accelerated in the course of a feeding operation, and retardation attains its maximum approximately when a sheet arrives at the front 30 gauges 14.

The rollers 5 are each similarly provided with a toothed wheel 15 on the other side of the table. The toothed wheels 15 mesh in pairs with an intermediate gear 16. The first roller 5 is directly driven from a sprocket wheel 17 on the shaft 9 by means of the chain 18.

Above the feed rollers pressure means, as rollers or, as shown in the drawings, balls 19 disposed in retaining cages, are provided in known manner, which can be rendered operative or inoperative in the usual way, not shown. The ball retainers are arranged on a lattice whose longitudinal bars 20 are displaceable in guides 21 in the direction of travel of the sheets, so that by longitudinal displacement of the lattice the balls 19 can be shifted from a roller 4 to a roller 5, and vice versa.

The pressure means cooperating with the feed rollers 4, 5 are reversible, so that the pressure means coacting with the slow roller 4 and those coacting with the high speed roller 5 may be alternately brought into and out of operative position. For this purpose, a cage containing a ball coacting with a roller 4 and another cage containing a ball coacting with a roller 5 are arranged in pairs on carriers 20 which are adjustably disposed on a rocking shaft 23 extending transversely over the width of the roller feed table. The rocking shaft 23 is provided on one side of the table with an arm 24 which by an articulated rod 25 is connected with one end of a double-armed roller lever 27 movably disposed at 26. By means of a tension spring 29 the roll 28 of the lever 27 contacts with the periphery of a cam 30 on the shaft 9.

The pressure rolls 6 coacting with the first roller 4 and one of the rolls 31 cooperating with the first high speed roller 5 form a pair connected by a common bearing lever 32, so that by corresponding setting of the lever 32 either one roll 6 can be made to cooperate with the first roller 4 or the other roll 31 to coact with the first roller 5. The roll carriers 32 are positioned on a shaft 33, and one arm 34 of the shaft 33 is articulated by a rod 35 to one arm of a double-armed roller

lever 36 whose roll 37 is drawn by a spring 38 against the circumference of a cam 39. A sheet moved by the cooperation of the roll 6 with the first roller 4 is conveyed at the higher speed, when the pressure roll 6 is lifted off from the roller 4, owing to the simultaneously established coaction of the roll 31 and of the high speed roller 5. The automatic control of the roll carriers 32 like that of the carriers 20 can be stopped by fixing the levers 25, 31 against the action of their springs 27, 38 in the position at which their rolls do not contact with the cam. This fixing of the control levers 31, 25 is connected with the manually to be effected reversal of the balls 19 and of the lattice 20 in the following manner:

The lattice 20 provided with a handle 40 for reversal possesses a stop 41 which coacts with one arm of a double lever 43 movably disposed at 42. The other arm of the lever 43 is connected by a rod 44 with one arm of the roller lever 36 whilst the handle 40 acts directly upon the arm 24 of the lever system for reversing the cage carriers 20 to effect stopping. When the control rods are inoperative, the pressure roll 6 rests on the first low speed roller 4 and the balls 19 coacting with the last low speed roller 4 are in operative position. Furthermore, the balls between the first and last roller are adjusted for cooperation with low speed rollers 4.

This adjustment of the balls 19 and rolls 6 corresponds to overlapping sheet feed which is carried out in the usual manner, for instance by causing a sheet, separated from the pile at its rear edge and advanced, to be caught by the first feed roller 4 and the coacting pressure rolls 6 whose rhythmical control is stopped and to be forwarded to the front gauges 14 by means of the additional feed rollers 4 driven at the same speed, against which the sheets fed in overlapping manner are pressed by the correspondingly adjusted balls 19. At each rotation of the shaft 9 the rollers 4 are retarded and accelerated in such manner that the sheets strike the front gauges 14 at the lowest feeding speed of the rollers.

If the sheets are to be fed singly at a distance from one another, the pressure members, by displacement of the grating 20 by means of the handle 40, are so adjusted that they cooperate with the rollers 5, whereby simultaneously the automatic reversal of the cage carriers 20 and the control of the pressure rolls 6 as well as the associated rolls 31 are actuated. The process will then be as follows:

When a sheet forwarded by the first feed roller 4 and the pressure rolls 6 is caught by the next feed roller 5 rotating at higher speed and the pressure rolls 31 thereof after they have pressed down upon the roller 5, feeding is carried out at the higher speed, since simultaneously the pressure rolls 6 are lifted off from the roller 4 rotating at lower speed. Toward the end of the feeding operation the cage carriers 20 are reversed, whereby the balls 19 contained therein are lifted off from the last high speed roller 5 and the balls cooperating with the last low speed roller 4 are brought into operative position. The sheet is thus turned over from the high speed feed roller 5 to the low speed roller 4 and forwarded by the latter roller whose speed is slowed down still more by retarding means to the gauges 14. The preceding balls 19 are so adjusted that at this time the sheet is subjected only to the action of the balls disposed in the carriers 20.

As shown in Fig. 1, near the front gauges 14 preliminary stops 45 having the form of hooked

5 arms are secured to a rocking shaft 47 arranged on the underside of a feed plate 46. The shaft 47 possesses on one side of the table an arm 48 connected by a rod 49 with one arm of a double 10 roller lever 50 arranged at 26 the roller 51 of which is pressed by a tension spring 52 against the circumference of a cam 53. By means of the cam 53 the preliminary stops 45 are controlled in such manner that they are brought into the path 15 of the sheet when the balls are lifted from the last high speed roller 5 and are swung out again from the path when the balls are placed on the last low speed roller 4. In this way, the preliminary stops 45 insure the adjustment of the sheet travel to the lower feeding speed of the roller 4 and timely feeding of the sheets to the front 20 gauges.

It is evident that the reversal of the feeder from overlapping to single sheet feed, and vice 25 versa, can thus be effected during operation by the mere displacement of the handle 40.

I claim:

1. In a sheet feeding device, a plurality of 30 spaced fast moving conveyor means, a plurality of spaced slow moving conveyor means alternately disposed with relation to the fast moving means, means for alternately accelerating and decelerating the slow moving conveyor means, and a pressure device for pressing fed sheets against the conveyor means and selectively operable with the fast moving and slow moving conveyor means.

2. In a sheet feeding device, a plurality of 35 spaced fast moving conveyor means, a plurality

of spaced slow moving conveyor means alternately disposed with relation to the fast moving means, means for alternately accelerating and decelerating the slow moving conveyor means, a pressure device for pressing fed sheets against the conveyor means and selectively operable with the fast moving and slow moving conveyor means, and shifting means for moving the pressure means from one conveyor means to the other.

3. In a sheet feeding device, a fast moving conveyor means, slow moving conveyor means alternately disposed with relation to the fast moving means, a pressure device for pressing fed sheets against the conveyor means and selectively operable with the fast moving and slow moving conveyor means, shifting means for moving the pressure means from one conveyor means to the other, and retarding means acting to retard the slow moving means at timed intervals.

4. In a sheet feeding device, a fast moving conveyor means, slow moving conveyor means alternately disposed with relation to the fast moving means, a pressure device for pressing fed sheets against the conveyor means and selectively operable with the fast moving and slow moving conveyor means, front gauges at the delivery end of the conveyor means, and cam actuated means to effect simultaneous depression of the front 20 gauges and shifting of the pressure means from the fast moving conveyor means to the slow moving conveyor means.

GEORG SPIESS.
